BRAKING DEVICE

Waldemar C. Ewaldson, Chicago, Ill., and Daniel V. Waters, Cranford, N. J., assignors to Western Electric Company, Incorporated, New York, N. Y., a corporation of New York

Application September 15, 1934, Serial No. 744,108

6 Claims. (Cl. 188—75)

This invention relates to a braking device and more particularly to a braking device for controlling intermittently operative rotary machines such as punch presses.

5 One widely used form of punch press has a power shaft driven in continuous rotation by a motor and having a heavy fly wheel thereon. A crank-shaft is arranged to be coupled to and uncoupled from the power-shaft by a clutch actuated by a treadle, lever or other means. A punch is actuated by a pitman driven by the crank-shaft and coacts with a die rigidly supported on the frame of the machine. For some kinds of work a "non-repeat" mechanism may be provided 15 whose function is to automatically disengage the clutch at the end of one revolution of the crank-shaft whether the treadle be released or not.

An object of the present invention is to provide simple, reliable and adjustable means to obviate 20 backlash in the coupling between the power-shaft and the crank-shaft of such machines and to ensure the stopping of the crank-shaft in an accurately predetermined position.

One form in which the invention may be embodied comprises a two part friction brake encircling and floating on the shaft, one part being 25 in continuous contact with the shaft to prevent backlash and means being provided to apply the other part of the brake to the shaft under adjustable pressure. The brake may in some instances be conveniently arranged to be actuated by the treadle or other device which controls the clutch.

Other objects and characteristic features of the invention will appear from the following detailed 30 description of one embodiment thereof taken in connection with the accompanying drawing in which the same reference numerals are applied to identical parts in the several figures and in which

40 Fig. 1 is a broken view in side elevation of a punch press provided with a brake mechanism constructed in accordance with the invention and having the pitman removed for clarity, and

45 Fig. 2 is a fragmentary view thereof in rear elevation.

In the embodiment of the invention herein disclosed a punch press of well known construction has a generally C-shaped frame 20 having a horizontal bed 21 to hold a die and a vertical guideway 50 22 to guide a pitman (not shown). A crank-shaft 23 is journaled horizontally in the upper part of the frame and may be coupled to and uncoupled from a power-shaft (not shown) by means of a clutch device (not shown) actuated by a pull 55 rod 24 pivoted on a lever 25 rigidly attached

to a shaft 26 journaled in the frame 20. A treadle lever 27 pivoted on the frame has one end of a pull rod 28 pivotally secured thereto, the other end of which is pivoted to the lever 25. A second lever 29 is also rigidly secured to the shaft 26 and has the lower end of a pull rod 30 pivotally attached thereto. The other end of the pull rod 30 is pivoted to the rear free end of a one arm lever 31 pivoted on a stub shaft 32 mounted in the frame 20. The lever 31 is provided with an integral 10 or rigidly attached cam block 33 located coaxially with the shaft 32.

A pair of semi-circular brake shoes 34 and 35, pivotally joined at 36 surrounds the shaft 23 and each is provided with a friction lining 37 of leather 15 or other appropriate material. Each of the shoes is formed opposite to the pivot 36 with a slotted outwardly extending lug 38 and 39 respectively. A bolt 40 having a laterally extended head 41 has its threaded body 42 located in the slots of the lug 20 39. The bolt head 41 has a broad lower portion bearing against the under side of the lug 38 and a narrower upper portion located freely in the slot of the lug 39 in position to be in contact with the under face of the cam block 33, the upper face 25 of which is in contact with the lug 39. A compression spring 43 presses at its lower end against the upper face of the lug 39 and at its upper end against a washer 44 surrounding the bolt body and held in place by adjustment nuts 45 on the threaded body of the bolt. 30

A supporting member 46 is secured to the frame and extends out therefrom under the shoe 35 and is formed with a vertically oriented aperture 35 across which extends a square cross-sectioned 40 guide 47 pivotally mounted in the member 46. The shoe 35 is provided with a pair of downwardly extending guide lugs 48 which embrace and slide with a small degree of looseness on the guide 47. A compression spring 49 is positioned between the lugs 48 and bears at its upper end against the shoe 35 and at its lower end against the head of an adjustment screw 50 mounted in the guide 47.

The lower shoe 35 is held at all times in contact 45 with the shaft 23 under an unvarying adjustable pressure caused by the spring 49 and floats on the shaft, being supported only by the spring 49 and guided by the lugs 48 coacting with the guide 47. The pressure of this shoe is regulable by 50 means of the screw 50 and tends to keep the crank-shaft dragging against the drive-shaft at all times to obviate any backlash between the crank-shaft and its drive. 55

When the lever 31 is in the position shown in

- full lines, i. e. when the operating treadle 27 is held down, the cam block 33 is turned to force the lug 39 up and the bolt head 41 down. This lifts the upper shoe 34 from the shaft without affecting either the lower shoe 35 or the pressure exerted thereon by the spring 49, since the bolt head is free to move in the slotted lug 38. When the treadle is released, the spring 51 forces the lever 31 into the position shown in dotted lines, 5 and the cam block 33 is rotated clockwise allowing the upper brake shoe 34 to move down and press on the shaft 23 under the pressure of the spring 43. Since the bolt head 41 now pulls up against the under side of the lug 38 the pressure 10 of the spring 43 also acts in this position to press the lower brake shoe 35 against the shaft.
- The apparatus disclosed above is thought of as a repeating press, i. e. one in which the crank-shaft 23 keeps on revolving as long as the treadle 20 27 is held down. When the treadle is released and moves up, the machine is so constructed that the clutch remains engaged until the offset part of the crank has passed its lowest position and is moving up. The springs 49 and 43 are so adjusted 25 that the momentum of the crank-shaft and its associated parts tending to continue the revolution of the crank-shaft will be dissipated by the brake as the crank reaches the top of its orbit.
- If the press be provided with a non-repeat device, the clutch is engaged and the crank-shaft set in motion, by depressing the treadle which action also lifts the upper brake shoe out of engagement with the shaft. In this case, however, 30 the non-repeat mechanism which automatically disengages the clutch as the crank moves up, is arranged to also automatically release the lever 31 to move from the full line position to the dotted line position thus allowing the spring 43 to move 35 the upper shoe down against the shaft.

The embodiment of the invention herein disclosed is merely illustrative and may be modified and departed from in many ways without departing from the spirit and scope of the invention 40 as pointed out in and limited only by the appended claims.

What is claimed is:

1. A braking device to act on a rotary member comprising a first brake shoe mounted to float on the rotary member in continuous contact therewith, first pressure exerting means to press the shoe against the member under constant pressure, a second brake shoe movably mounted with respect to the member, and second pressure exerting means to apply the second shoe to the member and to exert pressure of both shoes on the member, the second pressure exerting means being independent of the first pressure exerting means.
2. A braking device to act on a rotary member

comprising a first brake shoe mounted to float on the rotary member in continuous contact therewith, adjustable first pressure exerting means to press the shoe against the member under constant pressure, a second brake shoe 5 movably mounted with respect to the member, and adjustable second pressure exerting means to apply the second shoe to the member and to exert pressure of both shoes on the member, the second pressure exerting means being independent of the first pressure exerting means.

3. A braking device to act on a rotary member comprising a pair of brake shoes, one of the brake shoes being mounted to float on the rotary member in continuous contact therewith, first pressure exerting means to press the floating shoe against the member under constant pressure, means to apply the second shoe to the member and to disengage it therefrom, and second pressure exerting means to exert pressure of both 15 shoes on the member when the second shoe is applied thereto, the second pressure exerting means being independent of the first pressure exerting means.

4. A braking device to act on a rotary member 25 comprising a pair of brake shoes, one of the brake shoes being mounted to float on the rotary member in continuous contact therewith, adjustable first pressure exerting means to press the floating shoe against the member under constant 30 pressure, means to apply the second shoe to the member and to disengage it therefrom, and adjustable second pressure exerting means to exert pressure of both shoes on the member when the second shoe is applied thereto, the second pressure 35 exerting means being independent of the first pressure exerting means.

5. A braking device to act on a rotary member comprising a pair of semi-circular brake shoes pivoted together and encircling the member, first 40 pressure exerting means to keep one of the shoes in continuous contact with the member, means actuatable to engage the other shoe with the member, and second pressure exerting means to exert pressure of both shoes on the member.

6. A braking device to act on a rotary member comprising a pair of semi-circular brake shoes pivoted together and encircling the member, first 45 spring means to maintain one of the shoes in continuous contact with the member and to exert continuous pressure of the said shoe on the member, second spring means tending to engage the other shoe with the member and to exert pressure thereof against the member and to exert additional pressure of the first shoe against the 50 member, and means actuatable to disengage the second shoe from the member and to release the additional pressure of the first shoe.

WALDEMAR C. EWALDSON.
